UNITED STATES PATENT OFFICE.

JOHN H. BICKFORD, OF SALEM, MASSACHUSETTS.

VALVE.

SPECIFICATION forming part of Letters Patent No. 708,990, dated September 16, 1902.

Application filed June 17, 1901. Serial No. 64,831. (No model.)

To all whom it may concern:

Be it known that I, JOHN H. BICKFORD, of Salem, in the county of Essex and State of Massachusetts, have invented an Improvement in Valves, of which the following description, in connection with the accompanying drawings, is a specification, like letters on the drawings representing like parts.

This invention relates to valves and is intended as an improvement upon the valve shown and described in Letters Patent No. 686,703, granted to me November 19, 1901. In the valve shown in said patent the valve-plate was flexibly connected to its carrier and movable laterally against and held upon its seat by the pressure, and means were provided whereby an opposing force was exerted upon said valve-plate, which reduced the thrust of said valve-plate upon its seat. In said patent the valve-plate was adapted to remain in sliding contact with its seat or in contact with a suitable equivalent therefor at all times, and I find that with some types of valves and with valves of certain sizes this is objectionable.

My present invention has for its object to provide means for operating the valve-plate which is borne by the carrier in a different manner from that shown in said patent—that is to say, the valve-plate is movable toward and from its seat instead of being held upon and adapted to slide on its seat or on an equivalent at all times. In accordance with this invention the valve-plate borne by the carrier is moved laterally toward and from its seat by the pressure and is held upon its seat also by the pressure, and instead of providing means whereby an opposing force will be exerted upon said valve-plate to reduce its thrust upon the seat, yet cause it to slide at all times upon its seat or upon an equivalent therefor as the carrier is moved up and down, means are herein provided whereby the pressure which holds the valve-plate upon its seat is relieved or reduced to such an extent that under ordinary conditions the valve-plate is moved laterally away from its seat and remains away from its seat during the entire up-and-down movement of the carrier, except it may incidentally remain in contact with and slide on its seat a very short distance at the beginning of its upward movement and

at the end of its downward movement. Therefore herein the pressure when properly controlled, as will be hereinafter described, is employed for three distinct purposes, or, in other words, performs three distinct functions—viz., it moves the valve-plate laterally toward its seat, holds the valve-plate upon its seat when the carrier is at rest, and moves the valve-plate laterally away from its seat and holds it thus removed during the up-and-down movement of the carrier.

The valve is especially adapted for use in connection with elastic pressures, yet it may be used in connection with non-elastic pressures as well.

Figure 1 shows in vertical section a valve embodying this invention. Fig. 2 is a side elevation and partial section of the valve shown in Fig. 1, and Fig. 3 is a vertical section of a modified form of valve embodying this invention.

a represents the valve-case, which is made of any suitable shape, having ports *a'* *a'*, which are preferably made circular, and having a bonnet *f*, containing a stuffing-box, through which the valve spindle or stem passes. The valve-case *a* is formed or provided interiorly with a valve-seat *a*², surrounding or inclosing the port *a'*. The valve-seat *a*² may be made quadrangular or circular or of any other suitable shape.

The valve-plate herein shown consists of a disk *c*, connected to a follower-plate *c'* by a screw-threaded stud *e*, on which a nut is turned to hold the parts assembled, a suitable plunger (although not essentially necessary) being interposed between the plate *c'* and nut, which contains a spring *p*, to be described. The valve-plate is herein shown connected to a shell *d* (which is the essential element of the carrier which supports and carries the valve-plate) by a metallic or other diaphragm *c*², having a roll *c*³, and any suitable means will be employed for securing said diaphragm *c*² to the shell *d*—as, for instance, a ring *c*⁴ may be employed, which is screwed or otherwise connected to the shell *d*. The diaphragm *c*² serves as and constitutes a flexible element, and the follower-plate *c'*, which is located back of it, serves as a reinforcing-plate for said flexible element. Any other suitable flexible element may be employed in lieu

of a diaphragm. By connecting the diaphragm c^2 to the shell d it will be seen that a chamber is produced of which said flexible element forms a part, and said chamber is 5 herein employed to receive the pressure from the pressure-supply, as will be hereinafter described, and consequently will be herein referred to as the "pressure-chamber," although so far as my invention is concerned this 10 pressure-chamber may be constructed in other ways, yet having a flexible element as a part of it which is adapted to serve as an actuator for or means for moving the valve-plate when its movement is controlled, as will be herein- 15 after described, by the pressure in the pressure-chamber. The valve-plate is or may be provided at its lower end with a slot i , which establishes communication between ports as soon as said valve-plate is raised a short distance. 20 The valve-plate, herein shown as actuated by the flexible element of the pressure-chamber, is free to move laterally relative thereto in a direction toward and from its seat a^2 , according as the pressure in said pressure-chamber is controlled. Means are 25 provided whereby the pressure is admitted to the pressure-chamber, which latter, as herein shown, is located at the back side of the valve-plate, and said means, as herein shown, 30 consists of a fluid-passage or other connection which leads from the inlet of the valve, meaning the pressure-supply, to said pressure-chamber, which when open affords a free and unobstructed passage for the fluid which 35 is being controlled. This fluid-passage from the inlet of the valve—*i. e.*, the pressure-supply—to the pressure-chamber may be made in many different ways, more or less circuitous, which comes within the scope of this invention, and two different ways are herein 40 illustrated.

One form of fluid-passage is shown in Fig. 1, wherein it will be seen that the spindle or stem g , which is attached to the carrier, is 45 made tubular for a portion of its length, thereby providing a passage e^2 , which is in open communication with the pressure-chamber by means of a hole through the shell d , and at the upper end of said passage e^2 the spindle 50 or stem g has a side opening normally communicating with a recess in a gland w of the stuffing-box when the carrier is in its lower-most position and the valve consequently closed, and the bonnet f , containing said 55 stuffing-box in which said spindle rises, is cut away or formed to provide a passage e^3 , which is in open communication with the recess in the gland, and said bonnet and valve-case are provided with a passage e^4 , leading 60 from the passage e^3 . As shown in this figure of the drawings, the passages e^2 and e^4 are substantially in parallelism, while the passage e^3 is at right angles thereto and connects them at the top when the carrier is in the 65 position shown in Fig. 1. When the fluid-passage connecting the pressure-chamber with the pressure-supply is open, as shown

in said Fig. 1, the pressure in said pressure-chamber and acting back of the valve-plate will be the same per square inch as the pressure on the front side of the valve-plate; but as the area of the back side of the valve-plate acted upon by the pressure in the chamber is greater than the area of the front side of the valve-plate in contact with the pressure by the area of the seat it is obvious that the valve-plate will be moved laterally toward and held hard upon its seat by the pressure in said chamber acting back of it. The carrier bearing the pressure-chamber and valve-plate may be raised and lowered by turning the hand-wheel g^2 on the spindle or stem g . The spindle g passes up through a stuffing-box contained in the bonnet f , and a driving-gland f' is preferably provided, also 85 having a stuffing-box, which will be herein-after referred to as an "auxiliary" stuffing-box. The auxiliary stuffing-box is employed particularly in case the valve is used for controlling elastic pressures, yet may be employed for non-elastic pressures, if desired. Controlling the pressure in the pressure-chamber, which acts in turn to control the lateral movements of the valve-plate toward and from its seat, constitutes one of the essential features of this invention, and while this result may be accomplished in many different ways, all within the scope of this invention, I have herein shown one practical embodiment of the invention in Fig. 1 for the 95 sake of illustration. As shown in said Fig. 1, a valve is provided which is adapted to open and close the fluid-passage leading to the pressure-chamber to thereby admit or not the pressure and also to open and close 100 an outlet-passage leading from said pressure-chamber. The controlling-valve shown in said figure comprises as stationary members the aforesaid ring or gland w and the driving-gland f' and suitable packing, which in- 110 close or embrace the spindle g at the upper end of its tubular portion, which latter serves as the movable member of said controlling-valve, as will be described. The ring or gland w is formed with a suitable opening or recess 115 communicating with a passage e^3 in the bonnet f , and above said ring w a packing-ring w' is provided, which when compressed impinges upon a split ring w^2 , contained within it, into firm engagement with the spindle g . 120 The packing-ring w' is pressed down hard on the ring w , and thereby compressed, by the driving-gland f' . The lower end portion of the driving-gland f' has a vertical slot or passage f^3 contiguous the spindle g , extending 125 upward to an internal recess f^4 , and a hole v is provided at said recess, which establishes communication with the atmosphere. The slot or passage f^3 , recess f^4 , and hole v , taken together with the passage e^2 in the spindle 130 g , serve as and constitute an outlet-passage leading from the pressure-chamber. When the spindle g is in its lowermost position, Fig. 1, the side opening or entrance to the

passage e^2 in the spindle is in open communication with the opening in the ring w and the fluid-passage consequently open; but when said spindle is raised a short distance 5 said side opening or entrance rises above the opening in the ring w and is closed by the packing above said ring w , and said fluid-passage is at such time closed. As the spindle continues its upward movement the passage e^2 continues to rise above the ring or gland w and soon opens into the passage f^3 in the driving-gland f' , thereby opening the outlet-passage leading from the pressure-chamber. Thus in this instance that portion of 15 the spindle or stem g which co-operates with the stationary members of the controlling-valve to thereby control the fluid-passage and outlet-passage serves as the "valve proper" of the controlling-valve by which the pressure. 20 of the pressure-chamber is controlled. As soon as the controlling-valve closes the fluid-passage leading to the pressure-chamber the pressure in said pressure-chamber begins to fall, (if steam,) and when the pressure has been 25 reduced to a point where the pressure per square inch in the pressure-chamber is materially less than the pressure of the pressure-supply then the valve-plate will tend to fall away from its seat; but ordinarily the operator will not raise the carrier this short distance and then wait, even if steam, but will 30 continue to raise said carrier, and as soon as the controlling-valve opens the outlet-passage the accumulated pressure in the pressure-chamber will escape, which operation causes the valve to move laterally away from 35 its seat until the stud e strikes a stop in the shell d of the pressure-chamber.

As before stated, the fluid-passage leading 40 from the pressure-supply to the pressure-chamber may be constructed in many different ways; so, also, the outlet-passage leading from the pressure-chamber may be constructed in many different ways coming within the 45 scope of this invention. In the instance just described the valve controlling the fluid-passage and outlet-passage is operated by the means employed for moving the carrier; but said valve may be otherwise operated. It 50 will be seen as the carrier is raised the valve-plate incidentally will slide a short distance on its seat before said controlling-valve closes the fluid-passage.

The controlling-valve herein shown is simple and performs the work designed and intended for it; but so far as my invention is concerned a valve of any other form or construction may be employed in lieu of that herein shown, as I desire to include within 60 the spirit and scope of this invention any form or construction of valve adapted to open and close any form or construction of passage or passages connecting the pressure-supply with a pressure-chamber borne by the valve-plate carrier, whereby the pressure in said pressure-chamber may be controlled in such manner as to cause its flexible element to

move the valve-plate laterally toward and from its seat or cause the same to be so moved. w^3 represents another packing-ring below 70 the ring or gland w .

The outlet-passage leading from the pressure-chamber is quite as important in controlling the pressure in said pressure-chamber as the inlet-passage which leads from the 75 pressure-supply, as it is by opening said outlet-passage that the pressure is relieved, so as to cause the valve-plate to move away from its seat.

It will be seen that by properly controlling 80 the pressure in the pressure-chamber the valve-plate is operated, being moved laterally toward its seat by the pressure in said pressure-chamber and held in contact with its seat by the pressure in said pressure- 85 chamber and then moved laterally away from its seat by a decrease or absence of pressure in said pressure-chamber, all of which is controlled by the valve controlling the pressure of the pressure-chamber. 90

A spring p is contained in the plunger e' , which works in a socket formed in the shell d of the pressure-chamber, said plunger serving as a guide for the laterally-movable valve-plate, (although not essentially necessary,) 95 and said spring serving to seat the valve-plate normally and also assisting the pressure in seating it, as it might happen that when the valve-plate is away from its seat and there is a pressure back of it as well as in front of 100 it said valve-plate would be balanced so far as the pressure is concerned; hence the employment of this spring. To prevent the spring p from thrusting the valve-plate laterally against the interior wall of the valve-case, so that when lowered it will strike the projecting valve-seat, two ribs j , one on each side of the seat, are provided on said interior wall, on which the valve-plate may ride as it rises, being thereby held in a proper plane 105 to move correctly onto the valve-seat when lowered. 110

Referring to Fig. 3, a fluid-passage leading to the pressure-chamber borne by the valve-plate carrier is formed through the valve-seat, valve-plate, and stud e , being represented by the passage n through the valve-seat, the passage n' through the valve-plate, and the passage n^2 through the stud e , this modification being illustrated merely for the 115 purpose of showing another one of the various forms of fluid-passage from the supply to the pressure-chamber which may be employed. In this case the pressure in the pressure-chamber is exhausted into the body of 120 the valve and out into the opposite port when the valve is opened, as there is generally no pressure but atmospheric in this space, although substantially the same result would follow if there was a materially low pressure 125 in the outlet-port, and the body and opposite port serve as and constitute an outlet-passage leading from the pressure-chamber, and the controlling-valve which controls the pres- 130

sure of the pressure-chamber is formed by the valve-plate sliding a short distance on its seat and then opening the passage n' to the aforesaid outlet-passage.

5 It will be seen that herein the valve-plate is moved laterally toward its seat by admitting the pressure to the pressure-chamber and is closed upon its seat by the pressure assisted by the spring and thereafter is held 10 upon its seat by the pressure and is moved away from its seat by withdrawing or reducing said pressure in the pressure-chamber and allowing the pressure of the pressure-supply to force the valve-plate off of its seat, 15 and in case the valve controlling the fluid-passage is operated by the spindle or other means employed for moving the carrier it will be seen that said action is automatic.

What I do claim, and desire to secure by 20 Letters Patent, is—

1. In a valve, a carrier bearing a valve-plate and also bearing a pressure-chamber having a flexible element as a part of it, means for moving said carrier, means, as a passage, connecting said pressure-chamber with the pressure-supply, said pressure-chamber controlling the movements of said valve-plate laterally toward and from its seat as the pressure therein is controlled, and a valve 25 for controlling the pressure in said chamber, substantially as described.

2. In a valve, a carrier bearing a valve-plate and also bearing a pressure-chamber having a flexible element as a part of it, means for moving said carrier, means, as a passage, connecting said pressure-chamber with the pressure-supply, said pressure-chamber controlling the movements of said valve-plate laterally toward and from its seat as the pressure therein is controlled, and a valve for controlling the pressure in said chamber operated by the 30 means employed for moving the carrier, substantially as described.

3. In a valve, a carrier bearing a valve-plate and also bearing a pressure-chamber having a flexible element as a part of it, means for moving said carrier, means, as a passage, connecting said pressure-chamber with the pressure-supply, said pressure-chamber controlling the 35 movements of said valve-plate laterally toward and from its seat as the pressure therein is controlled, and a manually-operated valve for controlling the pressure in said chamber, substantially as described.

4. In a valve, a carrier bearing a valve-plate and also bearing a pressure-chamber having a flexible element as a part of it, means for moving said carrier, means, as a passage, connecting said pressure-chamber with the pressure-supply, said pressure-chamber controlling the 40 movements of said valve-plate laterally toward and from its seat as the pressure therein is controlled, and a spring acting to assist in moving said valve-plate toward its seat, substantially as described.

5. In a valve, a carrier bearing a valve-plate and also bearing a pressure-chamber having a

flexible element as a part of it, means for moving said carrier, means, as a passage, connecting said pressure-chamber with the pressure-supply, said pressure-chamber controlling the movements of said valve-plate laterally toward and from its seat as the pressure therein is controlled, a spring acting to assist in moving said valve-plate toward its seat and a valve for controlling the pressure in said pressure-chamber, substantially as described. 70

6. In a valve, a carrier bearing a valve-plate and also bearing a pressure-chamber having a flexible element as a part of it, means for moving said carrier, means, as a passage connecting said pressure-chamber with the pressure-supply including as a part of it a passage in the stem attached to said carrier, said pressure-chamber controlling the movements of 75 said valve-plate laterally toward and from its seat as the pressure therein is controlled, and a valve for controlling the pressure in said chamber, substantially as described. 80

7. In a valve, a carrier bearing a valve-plate and also bearing a pressure-chamber having a flexible element as a part of it, means for moving said carrier, means, as a passage, connecting said pressure-chamber with the pressure-supply, an outlet-passage leading from said pressure-chamber through which the pressure is released, said pressure-chamber controlling the movements of said valve-plate laterally toward and from its seat as the pressure therein is controlled, and a valve for controlling said outlet-passage, substantially as described. 95

8. In a valve, a carrier bearing a valve-plate and also bearing a pressure-chamber having a flexible element as a part of it, means for moving said carrier, means, as a passage, connecting said pressure-chamber with the pressure-supply, an outlet-passage leading from said pressure-chamber through which the pressure is released, said pressure-chamber controlling the movements of said valve-plate laterally toward and from its seat as the pressure therein is controlled, and a valve for controlling said outlet-passage operated by means employed for moving the carrier, substantially as described. 100

9. In a valve, a carrier bearing a valve-plate and also bearing a pressure-chamber having a flexible element as a part of it, means for moving said carrier, means, as a passage, connecting said pressure-chamber with the pressure-supply, an outlet-passage leading from said pressure-chamber through which the pressure is released including as a part of it a passage in a stem attached to said carrier, said pressure-chamber controlling the movements of 110 said valve-plate laterally toward and from its seat as the pressure therein is controlled, and a valve for controlling said outlet-passage, substantially as described. 115

10. In a valve, a carrier bearing a valve-plate and also bearing a pressure-chamber having a flexible element as a part of it, a reinforcing-plate for said flexible element, 120

means for moving said carrier, means, as a passage, connecting said pressure-chamber with the pressure-supply, said pressure-chamber controlling the movements of said valve-plate laterally toward and from its seat as the pressure therein is controlled, and a valve for controlling the pressure in said chamber, substantially as described.

11. In a valve, a carrier bearing a valve-plate and also bearing a pressure-chamber having a flexible element as a part of it, means for moving said carrier, means, as a passage, connecting said pressure-chamber with the pressure-supply, an outlet-passage 15 leading from said pressure-chamber through which the pressure is released, said pressure-chamber controlling the movements of said valve-plate laterally toward and from its seat as the pressure therein is controlled, and a valve 20 for controlling the pressure in said chamber constructed and arranged to close the passage leading from the pressure-supply to the pressure-chamber, and to open the outlet-passage leading from the pressure-chamber, substantially as described.

12. In a valve, a carrier bearing a valve-plate and also bearing a pressure-chamber having a flexible element as a part of it, means for moving said carrier, means, as a 25 passage, connecting said pressure-chamber with the pressure-supply, an outlet-passage leading from said pressure-chamber through which the pressure is released, said pressure-chamber controlling the movements of said

valve-plate laterally toward and from its seat 35 as the pressure therein is controlled, and a valve operated by the means employed for moving the carrier for controlling the pressure in said pressure-chamber constructed and arranged to close the passage leading 40 from the pressure-supply to the pressure-chamber, and to open the outlet-passage leading from said pressure-chamber, substantially as described.

13. In a valve, a carrier bearing a valve-plate and also bearing a pressure-chamber having a flexible element as a part of it, means for moving said carrier, means, as a passage, connecting said pressure-chamber with the pressure-supply, an outlet-passage 50 leading from said pressure-chamber through which the pressure is released, said pressure-chamber controlling the movements of said valve-plate laterally toward and from its seat as the pressure therein is controlled, and a 55 manually-operated valve for controlling the pressure in said chamber constructed and arranged to close the passage leading from the pressure-chamber and to open the outlet-passage leading from said pressure-chamber, substantially as described.

In testimony whereof I have signed my name to this specification in the presence of two subscribing witnesses.

JOHN H. BICKFORD.
